UNITED STATES PATENT OFFICE.

JOE S. SEABOALT, OF ABILENE, TEXAS.

STEAM-GENERATING APPARATUS.

Application filed October 4, 1926. Serial No. 139,426.

This invention relates to a steam generating apparatus, and has for its object to provide, in a manner as hereinafter set forth, an apparatus of such class for expeditiously 5 producing wet steam.

Further objects of the invention are to provide, in a manner as hereinafter set forth, an apparatus for producing wet steam, which is comparatively simple in its construction 10 and arrangement, strong, durable, compact, thoroughly efficient in its use, and comparatively inexpensive to set up.

With the foregoing and other objects in view, the invention consists of the novel construction, combination and arrangement of parts as hereinafter more specifically described, and illustrated in the accompanying drawings, wherein is shown an embodiment 15 of the invention, but it is to be understood that changes, variations and modifications 20 can be resorted to which fall within the scope of the claim hereunto appended.

In the drawings wherein like reference character denote corresponding parts 25 throughout the several views:

Figure 1 is a vertical sectional view of an apparatus for producing wet steam in accordance with this invention.

Figure 2 is a horizontal sectional view 30 thereof.

Figure 3 is a vertical sectional view of the boiler forming an element of the apparatus.

Referring to the drawings in detail 1 35 denotes a cylindrical jacket or shell having mounted upon its upper end a conoidal-shaped dome 2 which opens into an outlet flue 3. The jacket 1 provides a heating chamber 4 and arranged at the bottom of the 40 chamber 4 is a gas or oil burner 5 having a fuel supply pipe 6 connected therewith. The pipe 6 extends through and projects from the lower portion of the jacket 1 and is provided with a regulating cock or cut-off 7. The 45 pipe 6 communicates with a suitable source of supply, not shown. Suspended within the chamber 4 and spaced a substantial distance from the jacket 1 is a vertically disposed steam boiler 8 of circular cross section. The 50 boiler 8 extends from the upper end of the chamber 4 and has its lower end positioned a substantial distance above the burner 5.

The boiler 8 comprises a cylindrical body portion 9 of the desired diameter, a head 10 and a bottom 11. The head 10 and bottom 55 11 is formed from a flanged disk and the

flange of the latter is indicated at 12. The flanged disks are oppositely disposed with respect to each other and the flange of the disk which provides the head 10, is flush 60 with the upper edge of the body portion 9, and the flange of the disk which provides the bottom 11 is flush with the lower edge of the body portion 9. The head 10 is inset with respect to the upper end of the body 65 portion 9 and the bottom 11 is inset with respect to the lower end of the body portion 9. The head 10 centrally thereof is provided with an opening 13 and is further formed with an annular boss on its upper face which 70 extends upwardly from the head. The boss is indicated at 14 and its inner face forms a continuation of the wall of the opening 13. The inner face of the boss 14 as well as the wall of the opening 13 is threaded. The 75 bottom of the boiler is formed with a centrally arranged opening 15 and with an integral annular boss 16 which depends therefrom and the inner face of the boss 16 forms a continuation of the wall of the opening 15. The inner face of the boss 16, as 80 well as the wall of the opening 15 is threaded.

Fixedly secured to the wall of the opening 13 and the boss 14, that is to say threadably engaging with the boss 14 and wall of the opening 13 is a vertically disposed steam conducting pipe 17, which, extends through the dome 2 and into the flue 3 and has attached to its upper end a T-coupling 18. 85 Threadably engaging with the wall of the opening 15 and boss 16 is a depending inlet nipple 19 having its lower end connected to an inverted T-coupling 20.

The body portion 9 is formed with a pair 90 of superposed openings 21, 22. The opening 22 is the lower of said pair of openings and is arranged above the transverse median of the body portion 9. Integral with the body portion 9 and surrounding each of the 100 openings of said pair is a boss 23. Threadably engaging with the boss 21 as well as with the body portion 9 and seated in each of the openings of said pair is a gauge glass connecting pipe 24. The pipe connections 24 105 project through the jacket 1 and have connected with the outer ends thereof a gauge glass 25. The gauge is of known construction. The body portion 9 is furthermore provided, on that side opposite the side on 110 which is formed the openings 21, 22, with an opening 26 positioned above the opening

22 and integral with the body portion 9 and surrounding the opening 26 is a boss 27. Threadably engaging with the boss 27 and body portion 9, as well as communicating 5 with the exterior of said body portion 9, is a wet steam connecting line or rather delivery line 28 which has a cut-off or regulating cock 29. The line 28 extends through the jacket 1 and the cut-off or regulating cock is arranged exteriorly of the jacket. 10

Arranged within the heating chamber 4 and surrounding the boiler 8, is a pair of concentrically arranged sets of heating coils. The coils of the inner set are indicated at 30 15 and those of the outer set at 31. The coils of the outer set surround the coils of the inner set and the said sets of coils are positioned around the boiler 8 below the lower end of the gauge 25. The lower coil of the 20 inner set opens into an inlet pipe 32 which is arranged between the lower end of the boiler 8 and the burner 5. The inlet pipe 32 opens into the T-coupling 20. Arranged exteriorly of the jacket 1, at the lower portion 25 thereof is a blow-off valve 33 having a pipe connection 34 with the T-coupling 20. Connected with and opening into the lower coil of the outer set of coils is a combined steam and water supply pipe 33', provided with a 30 controlling valve 34' at its upper end and further communicating with an injector 35 which depends from a union 36. Communicating with the union 36 is a valved water supply line 37 and further opening into the 35 union 36 is a steam supply line 38. The union 36 has connected therewith a discharge nipple 39. The union 36 carries a controlling valve 40 which functions to control communication between the pipe 33' and the 40 lines 37, 38 and which further functions to control the discharge nipple 39.

The pipe 33' is arranged exteriorly of the jacket 1 and has its lower end formed with a right angular extension 41 which extends 45 through the jacket 1 and is coupled with the lower coil of the outer set 31. The steam supply line 38 is arranged exteriorly of the jacket 1 and dome 2 and has its upper end provided with a right angular extension 42 50 which projects through and into the flue 3 and is connected to the T-coupling 18. Arranged adjacent to the flue 3 is a pressure gauge 43, which has a pipe connection 44 with a safety valve 45, and the latter has a 55 pipe connection 46 leading therefrom and

extending into the flue 3 and connected to the T-coupling 18.

The boiler 8 and sets of coils 30, 31 are heated from the burner 5 and the heated contents of the sets of coils are delivered into the boiler 8 from the bottom thereof. The water is supplied through the line 37 to the pipe 33' and from there enters the lower coil of the outer set of coils, travels through said outer set and is discharged into the inner set and travels therethrough and is discharged from the lower coil of the inner set into the pipe 32 and supplied to the boiler 8 at the bottom thereof. The combined steam and water takes the same course, when the 70 steam is supplied by the pipe connections 17, 42 and 38. By this operation the production of wet steam is had and is furthermore had in an expeditious manner.

It is thought that the many advantages of 75 an apparatus for producing wet steam in accordance with this invention can be readily understood, and although the preferred embodiment of the invention is as illustrated and described, yet it is to be understood that 80 changes in the details of construction can be had which will fall within the scope of the invention as claimed.

What I claim is:

An apparatus for producing wet steam 85 comprising a vertically disposed jacket, a burner arranged within and at the lower portion thereof, a steam boiler positioned within the jacket and arranged over and above the burner, a pair of concentrically 90 arranged, vertically disposed sets of coils opening into each other at the top thereof, positioned within the jacket and surrounding the lower portion of the boiler, means positioned over the burner for establishing 95 communication between the lower coil of the inner set of coils and the bottom of the boiler, a supply line extending into the casting and opening into the lower coil of the outer set of coils, a water line leading to the 100 supply line, a steam supply line leading from the top of the boiler, extending from the jacket and communicating with the water supply line, a wet steam delivery line extending from one side of the boiler above said 105 sets of coils and projecting from the jacket.

In testimony whereof, I affix my signature hereto.

JOE S. SEABOALT.
